FRED R. TAISEY, OF LOWELL, MASSACHUSETTS, ASSIGNOR TO THE LAMSON COMPANY, OF BOSTON, MASSACHUSETTS, A CORPORATION OF NEW JERSEY.

CABLE-CARRIER APPARATUS.

1,157,193.

Specification of Letters Patent.

Patented Oct. 19, 1915.

Application filed February 24, 1914. Serial No. 820,721.

To all whom it may concern:

Be it known that I, FRED R. TAISEY, a citizen of the United States, residing at Lowell, in the county of Middlesex and 5 State of Massachusetts, have invented certain new and useful Improvements in Cable-Carrier Apparatus, of which the following is a specification.

The present invention relates to cable carrier systems and is an improvement in the apparatus described in my pending application Serial Number 779,449, filed July 17, 1913, entitled cable carrier system.

I have aimed in the herein described construction to accomplish all or substantially all that I have been able to accomplish by the improved drop-station apparatus disclosed in my said pending application; while at the same time overcoming certain 20 objectionable features present in said apparatus.

It has been found highly desirable, whenever practicable, in cable carrier systems and particularly in what is known as high-line apparatus, to so dispose the tracks that the carriers, of the type common in use today, and which carriers are particularly described in the patent to George A. Amsden Number 960,617, dated June 7, 1910, will 25 travel flatwise in contradistinction to edge-wise, or in other words, with the cover of the carrier when in its closed position, in a horizontal plane. In my said previous construction the carriers when passing a way or drop- 30 station traveled upon their sides or edges along the track which receives from said stations, but even in the construction therein shown, the carriers traversing the upper track, which delivers to said station were disposed flatwise; the two rails of the upper track being in a common horizontal plane.

In the present apparatus, however, both of the main tracks convey carriers flatwise; and as a result the system operates with 45 greater efficiency and safety, while the appearance of the stations is materially improved.

I have also aimed to provide a switching device by means of which carriers ascending 50 from a drop-station may be emplaced upon the receiving or forwarding track; the

switch proper being oscillatable in a horizontal plane.

I have also succeeded in mounting for movement in horizontal planes various other 55 elements which constitute important parts of the apparatus, such as the collision preventing trips and stops hereinafter referred to.

These and other objects of my invention 60 will be later discussed and the novel elements and combinations of means whereby said objects may be attained will be particularly set forth in the claims appended hereto.

In the drawings which form a part hereof and in which like reference characters designate like parts throughout the several views I have exemplified a preferred construction, but as I am aware of various 70 changes and modifications which may be made herein without departing from the spirit of my invention, I desire to be limited only by the scope of said claims broadly considered in the light of my disclosure. 75

Referring to said drawings: Figure 1 is a front elevation of an improved drop-station. Fig. 2 is a partial end elevation of the lower part of the apparatus shown in Fig. 1; said apparatus being drawn to a somewhat larger 80 scale herein. Fig. 3 is a similar end view of the upper portion of said apparatus. Fig. 4 is a top or plan view of the device shown in Fig. 1. Fig. 5 is a partial rear elevation of the upper part of said device. 85 Fig. 6 is a section taken on line VI—VI of Fig. 5, drawn to a somewhat larger scale.

The outgoing or forwarding track from the station has been designated 1 and the return track 2 is preferably in parallelism 90 with this forwarding track and directly thereabove; the rails of the respective tracks being in horizontal planes. The auxiliary track 3 which delivers carrier 4 up from the station proper to the main forwarding track 95 may have the usual opening 5 in the rails thereof to admit of the insertion of the lugs 4' of the carrier thereinto to permit of said carrier being emplaced upon said track.

Carriers to be delivered from the upper 100 track 2 to the station are selectively removed from said upper track by a switch 6 in a

known fashion; the said lugs 4' of such carriers emerging from their engagement with the rails of track 2 through the usual opening 7, and said carriers after traversing the switch, passing down to the station via the independent drop track 8, the lower extremity of which is looped quite sharply around in an arc of relatively small radius as at 8'. Here the received carriers come to rest and they may be removed either from the open end 9 of the independent track, at the right in Fig. 1, or through the usual opening 9' in said track, to the left of the station as viewed in said figure.

Tracks 3 and 8 are connected together by suitable brackets 10, which in turn may be supported by a hanger rod 11, which may, if desired, depend from the ceiling, or be supported in any other desired manner.

The cable, designated 12, runs parallel to the tracks 1 and 2 and is preferably continuous; the direction of travel thereof being indicated by arrows. Adjacent track 3 and normally substantially parallel thereto is a hoisting cord 13, the upper extremity of which is secured to a small drum 14 mounted upon a stud 15, the reduced extremity 15' of which may be screwed fast to an arm 16 by its nut 16'.

The upper extremity of the drum carries a pulley 17 which is grooved for driving engagement with the cable 12; the walls of this groove being knurled as at 17' to adapt them to better grip said cable.

The arm 16 is pivotally mounted upon a vertical spindle 18 which is journaled in suitable extensions or lugs of one of the brackets 19 which support the switch. Arm 16 is normally drawn into the position in which it is shown in full lines in Fig. 6 by a spring 20, but is capable of being swung around clockwise until the drum 14 and its non-revolvle casing 14' occupy the dotted line positions of these parts, in Fig. 6. At

such time an upward extension or catch 21, upon the arm 16 will have been moved into engagement with a latch 22, which is pivoted at 23 upon a bracket 23' carried by one of the rails of the track 3. The spindle 18 also has fixedly secured thereto and rotatable therewith a switch 24, the inner edge of which is adapted to complete the through track 1 across the gap in the rail thereof where carriers are delivered from track

3. The outer side of this switch also serves to practically complete the track 3, when the switch is in its dotted line position 24' shown in Fig. 6. At the point where the outer rail of track 3 runs into the corresponding rail of track 1, there is an elongated rib-like locking cam 25, which may be conveniently supported from the bracket 26 adjacent thereto, and this cam may also be used as a support for the free end of the switch 24 when the latter is in its full line

position shown in Figs. 4 and 6. The principal function of the locking cam 25, it may be here stated, is, however, to close the grip of carriers traversing track 1 past the switch, upon the cable, and also to correspondingly close the grip of carriers being despatched from the station, substantially as they enter track 1. To facilitate the engagement of the grips of such latter carriers with the cable, the switch carries upon its under side a somewhat triangularly shaped lug 27, best shown in Figs. 3 and 6. When the switch is in its open position 24' a roller 28 which is mounted thereupon is moved into engagement with the lower limb of the cable, while at the same time lug 27 will co-act with this roller to position said cable as indicated by dotted lines 12', in Fig. 6, the triangular extension 27 having depressed the cable slightly and permitted it to snap around the point at the bottom of said extension, when the switch was being opened. As a result of this disposition 12' of the cable, when the ascending carrier is propelled past the switch in the manner hereinafter described, its fixed or substantially fixed grip element 29 (see Fig. 2) will encounter the cable and push it toward its full line position shown in Fig. 6. Owing to the inclined surface provided by the inner edge of the lug 27 this action will depress the cable sufficiently to enable it to clear the bottom of the fixed gripping lug 29, whereupon the cable will snap over said lug and position itself between the pivoted grip element 29' and the fixed jaw, preparatory to being engaged by the carrier grip. The pivoted jaw then engages the grip closing or locking cam 25 which swings the jaw 29' inwardly in a known manner and the despatched carrier is then properly in engagement with the cable and will be propelled thereby along track 1 toward the cashier's station.

Through carriers traversing track 1 past the station shown do not have their engagement with the cable disturbed, and since switch 24 behaves in effect as a short rail across the gap at the point of emergence from track 3, said through carriers will be drawn quite smoothly and noiselessly past the station.

It will be observed that the through track 1 is substantially devoid of bends; there being in the present instance, however, a slight offset therein, the ends of which have respectively been designated 30 and 30'. This offset is provided so as to enable the cable 12 to be picked up by the grips of carriers being despatched, in the manner above described, but owing to the fact that the portion of track 1 intermediate points 30-30' is practically straight and quite extended, the cable is subjected to no undue stress by the drawing of carriers around abrupt

bends, and as above stated, the operation of the mechanism in so far as the passage of through carriers past a way station is concerned, is practically noiseless.

5 I shall now consider the preferred means for propelling carriers up from the station proper to and past the bridge 24.

In Fig. 1 the carrier 4 is shown in place upon track 3, with the lowermost portion of its fiber plate 31 in engagement with a bent metal strip 32 which is carried by and forms a part of a pusher 33. The inner end of the strip 32 may, if desired, be looped around as at 32' to form a handle. The pusher 33 10 rides guidedly between the rails of tracks 3, in much the same fashion as does the carrier, and has attached thereto, preferably at its lower extremity, the lower or free end of the hoisting cord 13. As previously 15 stated the upper extremity of this cord is attached to a drum 14 and when the hook 32' is engaged by the finger and pushed downwardly, the downward pull upon the cord 13 swings said drum into its dotted line position, above referred to, and the latch 22 becomes operative to hold said drum in such position.

The pulley 17 will at such time be driven by the lower limb of the cable 3, clockwise 20 as viewed in Fig. 6; free lateral movement of said cable by the pressure of said pulley thereagainst being resisted upon one side of said pulley by the idler 28 carried by the switch 24, which will at such time occupy 25 its dotted line position and upon the other side of the pulley 17 by an idler 34. This insures a proper driving engagement between pulley 17 and the cable, which winds the hoisting cord 13 up spool fashion upon 30 drum 14 until the carrier has been propelled preferably at least part way around the curve at the upper extremity of track 3, whereupon a lug or extension 35 carried by the pusher 33 is brought into engagement 35 with a small bumper or coil spring 36 carried by an arm 37 which is preferably integrally united to the latch 22, so that the latch is moved toward its unlatched or open position against the action of its spring 37'; 40 freeing the lug or tooth 21 and permitting spring 20 to return arm 16, pulley 17 and the drum 14 to their respective normal positions.

The present mechanism also preferably 45 comprises means for preventing collision between through carriers traversing track 1 and a part of the apparatus displaced into the path of said carriers upon the despatch of a carrier along track 3; my said pending application having also included a disclosure 50 of means to this end. In effect the said previously disclosed means have been modified herein to adapt them to the present construction wherein the through carriers traverse track 1 flatwise in manner aforesaid.

65 Connected to the arm 16 at 38 is a rod or

strip 39 which extends in parallelism with track 1 and has pivotally connected thereto the arms 40 and 41 of bellcranks which are respectively pivoted at 42 and 43 to a bar 44 which constitutes a part of the frame 70 work of the drop-station. The other arm 40' of the outer of these bellcranks carries a grip opening cam 45, which is adapted when in its dotted line position 45', shown in Fig. 6, to engage the pivoted grip elements of through carriers to free the cable therefrom, without, however, stopping such carriers. Correspondingly the arm 41' of the inner bellcrank has the extremity 46 thereof hooked or otherwise suitably shaped 75 to adapt it to engage and swing open the pivoted jaws of a carrier which may have succeeded in passing the cam 45 without being actuated by the latter, in such case as where, for example, the bar 39 is moved to the right after a carrier has passed cam 45 but before it can possibly encounter cam or hook 46. This latter is not only adapted to open the grip of a carrier which may be moved into engagement therewith, but is 80 furthermore adapted to stop or limit the further progress of said carrier, which cam 45 is preferably not adapted to do. As a result of this arrangement should there be, for example, two or even three carriers en 85 route along track 1 and closely following each other, and when the first of such a group of carriers would collide with the switch, said first carrier would have its grip opened by cam 45 and would come to 90 rest against hook 46; the second would correspondingly have its grip opened by cam 45 and would come to rest against the first carrier and so on.

Obviously any desired number of carriers 105 might thus be stored one behind the other to the rear of hook 46, if rod 39 be sufficiently extended and cam 45 correspondingly spaced from the cam or hook 46. By reason of the pivotal connection between rod 39 and arm 16, which latter is, as previously 110 stated, rigidly connected to the switch, whenever the switch is open cams 45 and 46 will be in their operative positions, while whenever the switch is in its full line position shown in Fig. 6, said cams will be to 115 one side of the path of the grips of through carriers traversing track 1.

In addition to actuating cams 45 and 46, rod 39 has a further function since it is 120 adapted to swing closed the pivoted jaw of the grip of any carrier which may be above said rod, when the rod is moved into its full line position in which it is shown in Fig. 6, which movement is of course simultaneous 125 with the emplacement of movable cams 45 and 46 in their inoperative positions. Thus, as soon as the carrier being despatched has passed the switch and the latch 22 has been tripped, not only will the switch move to a 130

position to clear track 1 but at the same time cams 45 and 46 will be withdrawn from the path of the grips of carriers traversing upon said track, and further those carriers which may have been stopped by cam 46 will be reengaged with the cable to pursue their course toward, for example, the cashier's station.

The remaining features of the construction such, for example, as the bracket 47 for aiding in removing the cable from carriers which are being switched onto the drop track 8, and the guide 48 above said switch, are well known in the art. I also prefer to provide some means for checking the descent of carriers passing down track 8 and to this end employed the known expedient of normally springing the rails of said track inwardly toward each other by means of springs 49, as indicated in Fig. 2, but I herein make no claim to such provision.

The operation of the exemplified apparatus is as follows:—Carriers traversing track 2 will normally pass the given drop-station unless said carriers are intended to be selectively removed from said track by the switch 6, in which case the so removed carriers will pass on to the drop track 8 in a known manner and will fall by gravity until they come to rest in the loop 8', from which they may be removed at either side thereof at the operative's convenience. Through carriers traversing track 1 will pass the given drop-station normally with their grips in continued engagement with the cable, but if a carrier is being despatched from the drop-station which would collide with such a through carrier the movement of switch 24 from its normal position will have so disposed cams 45 and 46 as to release such a through carrier and hold it upon track 1 adjacent hook 46. Cam 45 will at such time serve to disengage any closely succeeding carriers to avoid undue wear and tear upon the cable, and all of the so stopped carriers will be automatically reengaged with the cable by the rod 39 simultaneously with the movement of switch 24 back into its normal position. This action of rod 39 upon the pivoted grip 29' of any carrier which may be above said rod will be apparent upon an inspection of Fig. 2, since it is evident that pressure upon said jaw from the right, such as will be exerted thereagainst by the lateral movement of rod 39, will suffice to swing jaw 29' through its slot toward the fixed or relatively fixed jaw 29 until the engagement of the cable with jaw 29', aided by the spring which is usually provided in connection with the pivoted jaw in carriers of this description, will pull jaw 29' into its cable gripping position.

When a carrier is to be despatched from the drop-station it is inserted into engagement with track 3 interiorly of loop 8', as

shown in Fig. 1, its lugs 4' passing through aperture 5 in track 3 and the carrier then settling down until its fiber plate 31 is in engagement with the member 32 of the pusher 33. At such time the lugs 4' of the carrier will be below the aperture 5 in track 3 so that there will be no danger of the carrier inadvertently dropping out of engagement with said track. The hook or handle 32' is then pressed down, or if desired, the carrier itself may be pressed down by the fingers of the operator, which pulls over arm 16 through the intermediacy of the unwound hoisting cord 13 and its spool or drum 14. The arm 16 is thereupon locked in position by the latch 22 so as to hold the pulley 17 firmly in engagement with the cable which will be bowed slightly between the idlers 28 and 34. The hoisting cord 13 will then be wound up on its drum by power derived from the cable, and the pusher 33 will drive the carrier 4 up to and around the bend in track 3 which delivers to track 1. As the carrier passes the open switch the hook or projection 35 on the pusher engages spring 36 and thereby unlatches arm 16 and allows its spring 20 to retract pulley 17 from engagement with the cable, to swing the switch 24 so as to clear track 1, to retract cams 45 and 46 from their operative positions and to reengage the grips of any carriers which may have been freed by said cams from the cable, through the intermediacy of the bar or rod 39. The pusher 33 has sufficient weight to return it to the position in which it is shown in Fig. 1, and the apparatus is thereafter again ready to despatch a carrier from the station.

While the herein described construction is in many respects similar to the apparatus described in my pending application, it possesses several advantages thereover; one being that, as previously stated, carriers traversing track 1 past the drop-station travel flatwise, which obviates twisting or bending the through track through 90° as each station is approached and again at a point beyond said station; practice having demonstrated the desirability of conveying carriers flatwise wherever feasible.

The appearance of the station is also greatly improved as an inspection of Fig. 1 of the drawings herein will show, there being virtually in evidence at the station proper but the despatching track 3, the drop track 8 with its loop and the small pusher with its attached hoisting cord, the hanger 11 or other support with its brackets, by means of which the respective tracks are maintained in their determined relationship. The station is hence reduced to a skeleton-like frame and has in practice been found to be positive and reliable in its action.

In conclusion I wish to direct particular

attention to the delivery of a carrier being despatched from the station, to the main or forwarding track through a normally bridged gap in but one of the rails of the latter and in a plane which is substantially that of said forwarding track. By reason of this construction not only is the entrance of the carrier upon the forwarding track rendered easy and certain, but the station is 5 improved in appearance, the switch and most of the other movable parts moving in horizontal planes and their movements hence being less noticeable than when they are moved vertically, provided the main 10 tracks be not elevated.

Having thus described my invention what I claim is:

1. Cable carrier drop-station apparatus comprising an elevated forwarding track 20 adapted to convey carriers flatwise past the drop-station, an auxiliary track leading up from the station to said track and adapted to enter said carriers upon said forwarding track along a path the latter part of which 25 is substantially in the plane of said track, through a gap in one of the rails of the latter, a switch movable about a substantially vertical axis and adapted to guide carriers traversing said forwarding track past said 30 station safely by said gap, means including a cable for positively propelling a carrier along said auxiliary track from said station toward said switch, and for thereafter propelling said carrier along said track, and 35 means to move said switch automatically in at least one direction.

2. Cable carrier drop-station apparatus comprising an elevated forwarding track adapted to convey carriers flatwise past the 40 drop-station, an auxiliary track leading up from the station to said track and adapted to enter said carriers upon said forwarding track along a path the latter part of which is substantially in the plane of said track, 45 through a gap in one of the rails of the latter, a switch movable about a substantially vertical axis and adapted to guide carriers traversing said forwarding track past said station safely by said gap, means including 50 a cable for positively propelling a carrier along said auxiliary track from said station toward said switch and for thereafter propelling said carrier along said track, and means to move said switch substantially 55 horizontally to open communication between said auxiliary and forwarding tracks and to thereafter return said switch automatically to a position to leave the forwarding track clear for through carriers passing 60 said station thereover.

3. Cable carrier drop-station apparatus comprising an elevated forwarding track adapted to convey carriers flatwise past the drop-station, an auxiliary track leading up

from the station to said track and adapted 65 to enter said carriers upon said forwarding track along a path the latter part of which is substantially in the plane of said track, through a gap in one of the rails of the latter, a switch adapted to guide carriers traversing said forwarding track past said station safely by said gap, means including a cable for positively propelling a carrier along said auxiliary track from said station toward said switch and for thereafter propelling 70 said carrier along said track, and means to move said switch, to open communication between said auxiliary and forwarding tracks, when said propelling means is rendered operative to despatch a carrier 75 from said station.

4. Cable carrier drop-station apparatus comprising an elevated forwarding track adapted to convey carriers flatwise past the drop-station, a fixed curved auxiliary track 85 up and around which a carrier may be propelled from the station to said forwarding track, a switch at the point of delivery of said carrier to said forwarding track, and means co-acting with said auxiliary track 90 and switch, to enter said carrier upon said forwarding track along a path the latter part of which is substantially in the plane of said forwarding track and which leads into the latter through but one of the rails 95 thereof.

5. Cable carrier drop-station apparatus comprising an elevated forwarding track adapted to convey carriers flatwise past the drop-station, a fixed curved auxiliary track 100 up and around which a carrier may be propelled from the station to said forwarding track, a switch at the point of delivery of said carrier to said forwarding track, and means, co-acting with said auxiliary track 105 and switch, to enter said carrier upon said forwarding track laterally through but one of the rails of said forwarding track.

6. Cable carrier drop-station apparatus comprising an elevated forwarding track 110 adapted to convey carriers flatwise past the drop-station, a fixed curved auxiliary track up and around which a carrier may be propelled from the station to said forwarding track, a switch at the point of delivery of 115 said carrier to said forwarding track, and means, including a flexible hoisting element, co-acting with said auxiliary track and switch, to enter said carrier upon said forwarding track laterally thereof and in the 120 plane of said forwarding track.

7. Cable carrier drop-station apparatus comprising an elevated forwarding track adapted to convey carriers flatwise past the drop-station, an auxiliary track up which a 125 carrier may be propelled from the station to said forwarding track, and means, co-acting with said auxiliary track to enter said car-

rier upon said forwarding track laterally thereof in a plane which is substantially that of said forwarding track.

8. Cable carrier drop-station apparatus comprising an elevated forwarding track adapted to convey carriers flatwise past the drop-station, an auxiliary track up which a carrier may be propelled from the station to said forwarding track, and means, co-acting with said auxiliary track to enter said carrier upon said forwarding track laterally thereof in a plane which is substantially that of said forwarding track, said means including a power driven flexible element and a part driven thereby adapted to directly engage said carrier to propel the same along said auxiliary track.

9. Cable carrier drop-station apparatus comprising an elevated forwarding track adapted to convey carriers flatwise past the drop-station, an auxiliary track up which a carrier may be propelled from the station to said forwarding track, and means, co-acting with said auxiliary track to enter said carrier upon said forwarding track laterally thereof in a plane which is substantially that of said forwarding track, said means including a power driven flexible element, a part driven thereby adapted to propel said carrier along said auxiliary track and means, directly engageable with said flexible element, to drive said part.

10. Cable carrier drop-station apparatus comprising an elevated forwarding track adapted to convey carriers past the drop-station, an auxiliary track up which a carrier may be propelled from the station to said forwarding track, and means co-acting with said auxiliary track to enter said carrier upon said forwarding track, said means including a pulley mounted for rotation about a substantially vertical axis, a power driven cable, means to engage and disengage said pulley and cable and means driven by said pulley for propelling said carrier along said auxiliary track.

11. Cable carrier drop-station apparatus comprising an elevated forwarding track adapted to convey carriers past the drop-station, an auxiliary track up which a carrier may be propelled from the station to said forwarding track, and means co-acting with said auxiliary track to enter said carrier upon said forwarding track, said means including a power driven cable, a pulley mounted for rotation about a substantially vertical axis and adapted to be driven by said cable and means driven by said pulley for propelling said carrier along said auxiliary track.

12. Cable carrier drop-station apparatus comprising an elevated forwarding track adapted to convey carriers past the drop-station, an auxiliary track up which a carrier may be propelled from the station to

said forwarding track, and means co-acting with said auxiliary track to enter said carrier upon said forwarding track, said means including a power driven cable, a pulley mounted for rotation about a substantially vertical axis and adapted to be driven by said cable, means driven by said pulley for propelling said carrier along said auxiliary track, and a switch, to guide said carrier into engagement with said forwarding track, 75 operatively connected with said pulley.

13. Cable carrier drop-station apparatus comprising an elevated forwarding track adapted to convey carriers past the drop-station, an auxiliary track up which a carrier may be propelled from the station to said forwarding track, and means co-acting with said auxiliary track to enter said carrier upon said forward track, said means including a power driven cable, a pulley mounted for rotation about a substantially vertical axis and adapted to be driven by said cable, means driven by said pulley for propelling said carrier along said auxiliary track, a switch operatively connected to said pulley and means to move said pulley into engagement with said cable and said switch into position to guide said carrier in manner aforesaid.

14. Cable carrier drop-station apparatus comprising a forwarding track adapted to convey carriers flatwise thereover past the drop-station, a cable to propel said carriers, a pulley mounted for movement in a plane substantially parallel to that of said forwarding track, a switch in said forwarding track connected to said pulley and movable therewith, and mechanism operated by said pulley to propel a carrier up from the station, past said switch, and into engagement with said forwarding track.

15. Cable carrier drop-station apparatus comprising a forwarding track adapted to convey carriers flatwise thereover past the drop-station, a cable to propel said carriers, a pulley mounted for movement in a plane substantially parallel to that of said forwarding track, a switch in said forwarding track connected to said pulley and movable therewith, mechanism operated by said pulley to propel a carrier up from the station, past said switch, and into engagement with said forwarding track, and means to hold said pulley in operative relationship to said cable.

16. Cable carrier drop-station apparatus comprising a forwarding track adapted to convey carriers flatwise thereover past the drop-station, a cable to propel said carriers, a pulley mounted for movement in a plane substantially parallel to that of said forwarding track, a switch in said forwarding track connected to said pulley and movable therewith, mechanism operated by said pulley to propel a carrier up from the station 135

past said switch, and into engagement with said forwarding track, and means to hold said pulley in operative relationship to said cable only while a carrier is being despatched from said station.

17. Cable carrier drop-station apparatus comprising an elevated forwarding track adapted to convey carriers flatwise past the drop-station, an auxiliary track up which a carrier may be propelled from the station to said forwarding track, means, co-acting with said auxiliary track to enter said carrier upon said forwarding track laterally thereof in a plane which is substantially that of said forwarding track, and means for stopping a carrier en route along said forwarding track, past said station, when a carrier is being despatched from said station.

20 18. Cable carrier drop-station apparatus comprising an elevated forwarding track adapted to convey carriers flatwise past the drop station, an auxiliary track up which a carrier may be propelled from the station to said forwarding track, means to despatch a carrier from said station, and means for stopping a carrier en route along said forwarding track past said station, when a carrier is being despatched from said station.

30 19. Cable carrier drop-station apparatus comprising an elevated forwarding track adapted to convey carriers flatwise past the drop-station, an auxiliary track up which a carrier may be propelled from the station to said forwarding track, means to despatch a carrier from said station, and means for stopping a carrier en route along said forwarding track past said station, when a carrier is being despatched from said station, 40 and for automatically re-despatching the stopped carrier thereafter.

20. Cable carrier drop-station apparatus comprising an elevated forwarding track adapted to convey carriers flatwise past the drop-station, an auxiliary track up which a carrier may be propelled from the station to said forwarding track, a cable to propel carriers along said forwarding track, and means driven by said cable to propel a carrier up said auxiliary track, said means including a pulley of small diameter which said cable engages when said pulley is operative, the said engagement between said pulley and cable being along a relatively short arc and said pulley having its peripheral surface contoured to enable it to effectively grip said cable.

21. Cable carrier drop-station apparatus comprising an elevated forwarding track adapted to convey carriers flatwise past the drop-station, an auxiliary track up which a carrier may be propelled from the station to said forwarding track, a cable to propel carriers along said forwarding track, and means driven by said cable to propel a carrier up

said auxiliary track, said means including a pulley of small diameter which said cable engages when said pulley is operative, the said engagement between said pulley and cable being along a relatively short arc and 70 said pulley having a roughened surface to enable it to effectively grip said cable.

22. Cable carrier drop-station apparatus comprising an elevated forwarding track adapted to convey carriers flatwise past the drop station, an auxiliary track up which a carrier may be propelled from the station to said forwarding track, a cable to propel carriers along said forwarding track, means driven by said cable to propel a carrier up 75 80 said auxiliary track, said means including a pulley mounted for movement into and out of engagement with said cable, and means to move said pulley into engagement with said cable.

23. Cable carrier drop-station apparatus comprising an elevated forwarding track adapted to convey carriers past the drop-station, an auxiliary track up which a carrier may be propelled from the station to said 90 forwarding track, a cable to propel carriers along said forwarding track, means driven by said cable to propel a carrier up said auxiliary track, said means including a pulley mounted for movement into and out of 95 engagement with said cable, means for moving said pulley into engagement with said cable, and means, directly upon opposite sides of and adjacent to said pulley, to hold said cable properly with respect to said 100 pulley.

24. Cable carrier drop-station apparatus comprising a station, a forwarding track adapted to convey carriers past said station, a cable to propel carriers along said track, 105 an auxiliary track leading up from said station to said forwarding track, means to despatch a carrier from said station over said auxiliary track, said means including a pulley adapted for engagement with said cable 110 and means to engage said pulley with said cable, and means, upon opposite sides of and adjacent to said pulley, to hold said cable in firm engagement with said pulley.

25. Cable carrier drop-station apparatus comprising a station, a forwarding track adapted to convey carriers past said station, a cable to propel carriers along said track, an auxiliary track leading up from said station to said forwarding track, means to dispatch a carrier from said station over said auxiliary track, said means including a pulley adapted for engagement with said cable and means to engage said pulley with said cable, and revoluble means, upon opposite 120 sides of and adjacent to said pulley, to hold said cable in firm engagement with said pulley.

26. Cable carrier drop-station apparatus comprising an elevated track upon which a 130

carrier may be propelled from the station to said forwarding track, means, co-acting with said auxiliary track to enter said carrier upon said forwarding track laterally 5 thereof in a plane which is substantially that of the forwarding track, and means to prevent a collision involving said carrier, when being delivered to said forwarding track,

and a second carrier en route along said forwarding track past said station.

10

In testimony whereof I have affixed my signature, in the presence of two witnesses.

FRED R. TAISEY.
